BOTTLE

Regis Meyers, Arcadia, Calif., assignor to Sunkist Growers, Inc., Los Angeles, Calif., a corporation of California

Application July 23, 1954, Serial No. 31,573

Term of patent 14 years

(Cl. D58—8)

FIG. 1.

FIG. 2.

The unstippled portions of the bottle contrast in appearance with the stippled portions thereof in Figure 1 of the drawing.

The dominant feature of my design resides in the portion shown in full lines.

I claim:

The ornamental design for a bottle, as shown and described.
